[57] **ABSTRACT**

The invention provides an installation for cooling calcium carbide run off into vessels, comprising a rail system carrying trucks which serve as tapping vessels and are disposed under and at a distance from the tapping level of the calcium carbide furnaces, a movable device for ejecting the carbide blocks from the trucks, and a plurality of juxtaposed inclined planes which are constructed as chutes and the upper ends of which are disposed near a portion of the rail system which extends rectilinearly over a substantial length, while their lower ends lead to a conveyor belt. The trucks each have an upper portion which is lifted from a flat base to allow the blocks to be pushed off onto the chutes when they are cooled to a surface temperature of about 500°C to 600°C at which they are only partially solidified and just able to retain their block form without being supported laterally. The exposed blocks then rapidly cool to a temperature of about 200°C on the chutes which are overlapped to provide vents between them for the passage of cooling air below, between and above them.

INSTALLATION FOR COOLING CALCIUM CARBIDE RUN OFF INTO VESSELS

This application is a division of copending application for U.S. Letters Patent Ser. No. 24,542 filed April 1, 1970.

The invention relates to an installation for cooling calcium carbide which is run off into vessels.

In large furnaces, liquid calcium carbide is run off into crucibles which after being filled with calcium carbide are taken by means of a crane into a cooling hall. The filled crucibles are left for about 40 hours in the cooling hall until the calcium carbide has cooled to a temperature of about 200°C. The crucibles are then emptied, the carbide blocks coarsely crushed and this crushed calcium carbide is then loaded on to box belts which carry the coarse crushed calcium carbide to a fine crushing machine. In addition, a great deal of machinery in the form of portal cranes bridging the entire cooling hall are required to transport the crucibles from the tapping point to the hall, naturally with heavy expenditure for maintaining the mechanical equipment.

It is an object of the present invention to provide an installation for cooling calcium carbide run off into vessels, which greatly reduces cooling time, handling, labor and space requirements and simplifies transportation equipment. In accordance with this invention the installation comprises a rail system carrying trucks which serve as tapping vessels and are disposed beneath and at a distance from the tapping height of the calcium carbide furnaces; a movable device for emptying the tapping trucks and discharging carbide blocks to a plurality of juxtaposed inclined planes; the said movable device being comprised of a horizontally movable ejector ram, a platform and a holding ram, the said ejector ram being disposed at the height of the carbide blocks and the said platform being level with the trucks' bottom disposed opposite to the ejector ram and having inclining means associated to it, and the said holding ram being placeable on to the surface of the carbide blocks; the said inclined planes being constructed as chutes the upper ends of which are disposed near a portion of the rail system which extends rectilinearly over a substantial length, while their lower ends are positioned at a distance above a conveyor belt.

Each of the trucks have an upper portion which is lifted from a flat base to allow the blocks to be pushed off onto aligned chutes when they are cooled to a surface temperature of about 500° to 600°C at which they are only partially solidified and just able to retain their block form without being supported laterally. The exposed blocks then rapidly cool to a temperature of about 200°C on the chutes which are overlapped to provide vents between them for the passage of cooling air below, between and above them. This invention entails shorter cooling times and correspondingly smaller space requirements, while expenditure for machinery is restricted to a minimum. According to the invention, this is essentially achieved by first cooling the calcium carbide in the vessels to a surface temperature below 600°C, particularly between 500° and 600°C, thereupon extracting it in the form of a block from the vessels and in that form subjecting it to the action of the outer atmosphere on a conveyor device for cooling it down to a temperature of about 200°C which is suitable for crushing it. In this manner an installation of the type

first mentioned above for the cooling of calcium carbide run off into vessels is obtained which fully solves the abovementioned problems underlying the invention.

As the calcium carbide block is in contact over a large area with the air surrounding it, its cooling time is in particular reduced from 40 hours to about 18 hours. Since the crucibles previously are dispensed with, the space required or the cooling hall is correspondingly small. Since with the aid of the device the transport of the crucibles from the tapping point to the cooling hall is eliminated, the expenditure for machinery in the form of portal cranes and the like can also be reduced accordingly.

In accordance with a preferred feature of the invention the rail system comprises two elongated rail loops which have a common portion of track situated near the chutes and which at one head end enclose the calcium carbide furnace and run past its tapping holes.

A further preferred feature of the present invention comprises combining two installations so as to obtain a double installation, wherein the said installations are arranged opposite to one another in mirror image symmetry and the imaginary mirror plane runs perpendicularly through the conveyor belt. In this way it is readily possible for the output of two calcium carbide furnaces to be cooled in a single cooling hall associated with the two calcium carbide furnaces, and then further processed.

An example of embodiment of the invention is illustrated in the drawing. The invention is not restricted to the embodiment illustrated, but other arrangements are possible within the scope of the invention. In the drawing:

FIG. 1 is a plan view of the installation,
 FIG. 2 a cross-section through the installation on the line II-II in FIG. 1, on a distorted scale, and
 FIG. 3 shows part of the chute surface.

A rail system 14, 15, 16 runs past the calcium carbide furnace 13 equipped with the electrodes 10, 11, 12, in such a manner that the tapping trucks 17 and 18 are guided past the tapping holes (not shown) on the calcium carbide furnace 13. The rail system 14, 15, 16 comprises two rail loops 14 and 15, which have a common length of track 16 extending rectilinearly over a substantial length.

In the region of the rectilinear portion of track 16 a movable ejector device 19 is disposed on the rails 20 and 21. With the aid of the ejector device 19 the upper part 30 of the tapping truck 17, 18 and 22, respectively, can be lifted and the carbide block 24, which is already solid on its surface, ejected laterally on to one of the numerous inclined planes 23 serving as chutes. The carbide blocks 24 discharged onto the inclined planes 23 take up position in a row one behind the other. On the release of a flap 50 provided at the lower end of the chutes 23, the carbide block lying nearest the conveyor belt 25 can be ejected onto the latter in order to continue on the belt its path of the coarse crushing plant. The installation illustrated in FIG. 1 is a double installation, in which two of the installations described above are disposed opposite one another in mirror-image symmetry, the imaginary mirror plane extending perpendicularly through the conveyor belt 25.

In FIG. 2 shows a section along the line II-II in FIG. 1 on a distorted scale, and details of the ejector device 19. The latter is essentially so constructed that it serves

as a portal crane 28 with lifting gear 29 for lifting the conically shaped upper part 30 of the tapping truck off the bottom part 31 of the latter, while a horizontally movable ejector ram 32 is disposed at the height of the carbide block 24. The lifting gear 29 comprises a cross-beam 33, which at both ends is suspended by two ropes 34, 35 to a trolley 36, and two movable hooks 37, 38 engaging bosses 39 and 40 provided on the upper part 30 of the truck. The cross-beam 33 carries a holding ram 41 which during the operation of lifting the upper part 30 of the truck holds the carbide block 24 in position on the bottom part 31 of the truck. The holding ram 41 may be operated in any desired manner, but it is particularly advisable to provide hydraulic or pneumatic operation of the holding ram 41. The ejector ram 32, which is fastened on a framework 43 joined to the crane beam 42, may likewise be operated hydraulically, pneumatically or similarly. During the ejection the ejector ram 32 is supported against the rail 51 constructed as an abutment.

A platform 44 level with the bottom part 31 of the tapping truck is disposed opposite the ejector ram 32. This platform 44 is adapted to be swivelled by means of a draw device 45, so that it can be brought out of the horizontal position shown in solid lines into the inclined or swivelled position shown in broken lines.

The crane 28 moves as a whole by means of its wheels 46 on the rails 20, 21 which are supported on a number of pillars 48.

The abovedescribed ejector device is operated in the following manner. When the carbide block 24 has cooled sufficiently on its outer surface to enable it to retain its block form without being supported laterally, that is to say when it has cooled on its surface, the tapping truck 22 is brought beneath the ejector device. The hooks 37 and 38 are then attached to the bosses 39 and 40 on the tapping truck 22 and the holding ram 41 is lowered onto the carbide block 24 as illustrated in FIG. 2. The upper part 30 of the tapping truck 22 is then lifted off the bottom part 31, so that the carbide block 24 lies on the bottom part 31 of the tapping truck 22 without lateral support from the upper part 30. After the upper part 30 of the tapping truck 22 has been lifted off the ejector ram 32 is operated to push the carbide block 24 off the bottom part 31 of the tapping truck 22 and on the platform 44. The platform 44 is then swung into the position shown in broken lines in FIG. 2, so that the carbide block 24 can slide on the inclined plane 23, which is constructed as a chute. From this chute 23 the carbide block 24 passes after a corresponding cooling time onto the conveyor belt 25 and from the latter, after being cooled to a temperature of about 200°C, is delivered to the crushing part in which it is subjected first to coarse and then to fine crushing. As can be seen in FIG. 3, the chute 23 is vented by means of overlapping panels 49, in order in this way to intensify the cooling of the carbide blocks 24 by enabling them also to be cooled from below by the movement of air.

The following Examples are intended to demonstrate the beneficial effects offered by the installation according to the invention Example 1 was carried out with the use of a known installation, and Example 2 was carried out with the use of an installation according to the invention.

EXAMPLE 1

Liquid calcium carbide (295 litres of acetylene per kg of carbide) was cooled for 40 hours in a crucible until the surface temperature of the carbide block was about 200°C. The crucible was then emptied, the carbide block coarsely crushed and the crushed carbide was charged with a layer height of about 30 cm on to box belts the speeds of which were so adjusted that the carbide discharged from the last box belt after about 30 minutes had a temperature of about 150°C. The ten samples taken, in accordance with the rules for taking samples, after the comminution of the carbide to particles having a diameter of from 0 to 2 mm had a mean acetylene content of 293.5 litres per kg of carbide. The loss accordingly was 0.5 percent.

EXAMPLE 2

Liquid carbide (295 litres of acetylen per kg of carbide) was cooled in accordance with the invention in a tapping truck for 4 hours until the surface temperature of the block was about 600°C. The carbide block, which had solidified on its surface, was then removed from the truck and loaded on a conveyor belt which delivered the carbide block within 14 hours, during which time the block cooled to about 200°C, to the coarse crusher. The coarsely crushed carbide was then loaded in a layer height of about 30 cm on box belts the speeds of which were so adjusted that the carbide thrown off from the last box belt after about 30 minutes had a temperature of about 150°C. The ten samples taken, in accordance with the rules for taking samples, after comminution of the carbide to particles having a diameter of 0 to 2 mm had a mean acetylene content of 293.5 litres per kg of carbide. The loss accordingly was about 0.5 percent.

We claim:

1. An installation for cooling of calcium carbide which is run off into vessels, comprising a rail system carrying trucks which serve as tapping vessels and are disposed beneath and at a distance from the tapping height of calcium carbide furnaces; a movable device for emptying the tapping trucks and discharging carbide blocks to a plurality of juxtaposed inclined planes; the said movable device being comprised of a horizontally movable ejector ram, a platform and a holding ram, the said ejector ram being disposed at the height of the carbide blocks and the said platform being level with the trucks' bottom disposed opposite to the ejector ram and having inclining means associated to it, and the said holding ram being placeable on to the surface of the carbide blocks; the said inclined planes being constructed as chutes the upper ends of which are disposed near a portion of the rail system which extends rectilinearly over a substantial length, while their lower ends are positioned at a distance above a conveyor belt.

2. An installation as claimed in claim 1, wherein the rail system comprises two elongated rail loops which have a common portion of track situated near the chutes and which at one head end enclose the calcium carbide furnace and run past its tapping holes.

3. A double installation in which two installations as claimed in claim 1 are disposed opposite one another in mirror-image symmetry, the imaginary mirror plane extending perpendicularly through the conveyor belt.

4. An installation as set forth in claim 1, wherein each of the trucks comprises a flat base and a removable top

portion, the movable device including lifting gear connectable to the removable upper portion of the trucks for lifting it off of the blocks when they are surface cooled and partially solidified to a temperature at which they are just able to maintain their block form without lateral support.

5. An installation as set forth in claim 4, wherein the removable upper portions of the trucks have open tops through which the molten calcium carbide is tapped and the holding ram is placed on the partially solidified upper surface of the carbide blocks.

6. An installation as set forth in claim 5, wherein the movable device comprises a rail-mounted crane having a path of travel aligned with a portion of the rail system carrying the trucks.

7. An installation as set forth in claim 6, wherein a delivery platform is mounted on the crane between the trucks and the chutes, the ejector ram being mounted on the crane on the side of the trucks opposite from the delivery platform for pushing the blocks onto the delivery

5

platform, and tilting means reacting between the delivery platform and the crane for inclining the platform in line with the chutes for sliding the partially solidified blocks from the delivery platform, onto the chutes.

10

8. An installation as set forth in claim 4, wherein the lifting gear comprises a suspended crossbeam, the ejector ram being connected to a central portion of the crossbeam, and hook means for engaging the removable upper portion of the trucks being connected to the ends of the crossbeam.

15

9. An installation as set forth in claim 1, wherein gates are mounted at the ends of the chutes between the chutes and the conveyor belt for controlling the passage of the blocks to the conveyor belt.

20

10. An installation as set forth in claim 2, wherein the rail upon which the crane is mounted extends longitudinally within the elongated rail loops.
